DESIGN FOR A SURGICAL MASK

Grace Kemp, New York, N. Y.

Application March 31, 1944, Serial No. 113,101

Term of patent 3½ years

(Cl. D83—1)

To all whom it may concern:

Be it known that I, Grace Kemp, a citizen of the United States, residing at the city of New York, in the county of New York and State of New York, have invented a new, original, and ornamental Design for a Surgical Mask, of which the following is a specification, reference being had to the accompanying drawing, forming a part thereof.

In the drawing:

Fig. 1 is a side elevational view of a surgical mask showing my new design.

Fig. 2 is a reduced perspective view thereof in a position when in use.

Fig. 3 is a top plan view thereof.

Fig. 4 is a front elevational view thereof.

I claim:

The ornamental design for a surgical mask, substantially as shown.

GRACE KEMP.
